US00D673029S

(12) **United States Design Patent**
Apesteguia Martinez et al.

(10) **Patent No.:** US D673,029 S
(45) **Date of Patent:** ** Dec. 25, 2012

(54) **FURNITURE COMPONENT**

(75) Inventors: **Oscar Apesteguia Martinez**, Sarriguren (ES); **Ismael Bernaola Olivares**, Sarriguren (ES); **Francisco Javier Ullan Roldan**, Sarriguren (ES)

(73) Assignee: **Ingeteam Power Technology, S.A.**, Zamudio, Bizkaia (ES)

(**) Term: **14 Years**

(21) Appl. No.: **29/406,210**

(22) Filed: **Nov. 10, 2011**

(30) **Foreign Application Priority Data**

May 25, 2011 (EM) 001868480-0002

(51) **LOC (9) Cl.** **08-05**

(52) **U.S. Cl.** **D8/354; D8/349**

(58) **Field of Classification Search** D8/349, D8/354, 366, 374, 381, 382, 400, 394, 395, D8/356, 380, 371; 248/300, 222.14, 223.14, 248/224.61, 224.7, 316.1, 237, 309.1; 312/111, 312/140; 403/326, 381, 14, 169, 167; 52/238.1, 52/243.1, 394, 395, 578, 579, 584.1, 589.1, 52/188, 182, 191, 702, 712, 745.06, 189, 52/506.5, 586.1; 29/428, 525.01, 464, 14, 29/208, 205
